CLAIM

The ornamental design for a medallion, as shown and described.

DESCRIPTION

FIG. 1 is a left perspective view of the front side of a medallion;

FIG. 2 is a right perspective view of the back side of the medallion;

FIG. 3 is a front side view of the medallion;

FIG. 4 is a back side view of the medallion;

FIG. 5 is a top view of the medallion;

FIG. 6 is a bottom view of the medallion;

FIG. 7 is a right side view of the medallion; and,

FIG. 8 is a left side view of the medallion.

The broken lines in the Figures illustrate portions of the medallion that form no part of the claimed design.

1 Claim, 6 Drawing Sheets(56)
